UNITED STATES PATENT OFFICE.

WATSON BEEBE, OF DETROIT, MICHIGAN, ASSIGNOR TO METALLIC NOVELTY WORKS,
OF DETROIT, MICHIGAN, A COPARTNERSHIP.

FLY-TRAP.

1,093,599.

Specification of Letters Patent. Patented Apr. 21, 1914.

Application filed September 22, 1913. Serial No. 791,001.

To all whom it may concern:

Be it known that I, WATSON BEEBE, a citizen of the United States of America, residing at Detroit, in the county of Wayne 5 and State of Michigan, have invented certain new and useful Improvements in Fly-Traps, of which the following is a specification, reference being had therein to the accompanying drawings.

10 This invention relates to fly traps and particularly to an arrangement thereof whereby an ordinary glass jar may be employed and whereby a neat and inexpensive construction is obtained that is very effective in operation.

15 The invention consists in the matters hereinafter set forth and particularly pointed out in the appended claims.

In the drawings, Figure 1 is a view, partially in elevation and partially broken away and in section, of a fly trap that embodies features of the invention; Fig. 2 is a plan view of the trap with the jar removed, showing a section line I, I that indicates the plane of sectional view of Fig. 1; and 25 Fig. 3 is a view in detail of a base plate blank before application to the trap.

Referring to the drawings, a conoidal screen 1 of wire or other suitable material 30 is formed by indenting a suitable piece thereof in such manner as to present diamond-shaped mesh openings. An opening is formed at the crown or apex of the screen. The marginal portion 2 of the screen is bent 35 out to form a flange that overlies the marginal portion of a generally circular aperture 3 in a base 4. The latter is preferably formed of sheet metal with downturned marginal flanges 5 that support it at an interval from the surface on which it rests. Inwardly projecting tongues 6 are formed 40 around the periphery of the aperture 3 of the blank of the base 4. These are upbent and passed through the screen 1 whose mesh 45 strands are readily spread to widen the mesh openings sufficiently to permit this. The tongues are outbent over an inner annular flange 7 of a collar having a flange 9 that is screwthreaded or otherwise formed to 50 receive the neck 10 of an inverted jar 11 of translucent or transparent material. Preferably the collar is stamped out of sheet metal and is screw-threaded for connection with the mouth of an ordinary fruit jar.

In operation, the light through the jar attracts insects that crawl beneath the base so that the latter work their way up through the inner face of the screen and out through the opening at the apex of the screen. As the construction is very rigid the weight of 55 the jar does not tend to deform it and sufficient space is also insured by the use of the downturned end flanges of the base to permit the passage of flies or the like on to the base into the screen. By the disposition of 60 the screen and its formation as indicated, it may be secured in place without cutting any of its fibers so that it is not liable to work apart.

Obviously, changes in the details of construction may be made without departing from the spirit of my invention and I do not care to limit myself to the particular form or arrangement of parts.

What I claim is:—

1. A fly trap comprising a metal base plate resting on downturned end flanges and having a central aperture, a conical screen having a flange at its wider end superposed on the aperture margin of the base, a collar having an inner annular flange superposed on the flange of the screen and an upwardly extending flange, tongues formed on the base at the margin of the opening and bent upwardly to pass through the mesh of the screen and reverted on the collar flange, and an inverted jar having a neck detachably interlocked with the upper flange of the collar. 75

2. A fly trap comprising a metal base plate resting on downturned end flanges and having a central aperture, a conoidal screen having a flange at its wider end superposed on the aperture margin of the base, a collar having an inner annular flange superposed on the flange of the screen and an upwardly 80 extending flange, tongues formed on the base at the margin of the opening and bent upwardly to pass through the mesh of the screen and reverted on the collar flange, and an inverted jar having a neck detachably interlocked with the upper flange of the collar. 85

90 In testimony whereof I affix my signature in presence of two witnesses.

WATSON BEEBE.
